INDUSTRIAL THERMOMETER

Raymond J. Feldman, Bronx, N.Y., assignor to SOS Consolidated, Inc., Birmingham, Mich., a corporation of Nevada

Filed June 13, 1969, Ser. No. 17,697

Term of patent 14 years

Int. Cl. D10—09, 11

U.S. Cl. D52—7

FIG. 1

FIG. 7

FIG. 5

FIG. 3

FIG. 2

FIG. 4

FIG. 6

FIGURE 1 is a perspective view of the industrial thermometer showing my new design.

FIGURE 2 is a front view thereof.

FIGURE 3 is a side view thereof.

FIGURE 4 is an opposite side view thereof.

FIGURE 5 is a top plan view thereof.

FIGURE 6 is a bottom plan view thereof.

FIGURE 7 is a rear view thereof.

The broken lines are shown for illustrative purposes only and do not form part of the claim.

I claim:

The ornamental design for an industrial thermometer, as shown and described.
